US00D572688S

(12) **United States Design Patent**
Kim et al.

(10) **Patent No.:** **US D572,688 S**
(45) **Date of Patent:** **** Jul. 8, 2008**

(54) **MOBILE PHONE**

(75) Inventors: **Kuk-Hwan Kim**, Seoul (KR);
Sung-Hoon Hong, Suwon-si (KR);
Beom-Ku Han, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/260,497**

(22) Filed: **May 26, 2006**

(30) **Foreign Application Priority Data**

Feb. 6, 2006 (KR) 30-2006-0004167

(51) **LOC (8) Cl.** **14-03**

(52) **U.S. Cl.** **D14/138**

(58) **Field of Classification Search** D14/137,
D14/138, 147, 218, 247-248, 341-347; 455/90.3,
455/556.1, 566, 575.1, 575.3, 575.4
